UNITED STATES PATENT OFFICE.

OSCAR C. RIXSON, OF OAK PARK, ILLINOIS, ASSIGNOR TO THE OSCAR C. RIXSON CO., OF CHICAGO, ILLINOIS, A CORPORATION OF ILLINOIS.

DOOR-CHECK.

SPECIFICATION forming part of Letters Patent No. 766,387, dated August 2, 1904.

Application filed June 7, 1901. Serial No. 63,664. (No model.)

To all whom it may concern:

Be it known that I, OSCAR C. RIXSON, a citizen of the United States of America, residing at Oak Park, Cook county, Illinois, have invented certain new and useful Improvements in Door-Checks, of which the following, taken in connection with the accompanying drawings, is a specification.

My invention relates to means for closing and checking the closure of doors; and its principal objects are, to provide such door closing and checking means as will be readily invertible to use with either a left hand or right hand door; to provide means by which the actuating spring for closing the door operates in a direct line and by the same instrumentality as the checking device therefor; to provide a compact and self-contained means for actuating the door and checking it in its return motion; to provide superior means for using a liquid checking device, and to provide for entirely inclosing said liquid so as to relieve the joints of the higher pressure therein; to provide superior mechanism for carrying out the functions, and to generally simplify and improve the structure of such devices, as will be hereinafter explained.

In order to obtain a better understanding of my invention reference may be had to the accompanying drawings, in which in Fig. 1 I have shown in side elevation my improved door check applied to a door, and in Fig. 2 I have shown a plan view of the checking device, with the arms in normal position, when the door is closed, Fig. 3 is a horizontal section through my improved checking cylinder, with the parts in the position occupied when the door is closed, Fig. 4 is a like section with the parts in the position occupied when the door is open, Fig. 5 is a vertical section taken on the line 5 of Fig. 1, Fig. 6 is a section taken on the line 6 of Figs. 1 and 3, Fig. 7 is a section taken on the line 7 of Fig. 3, and Fig. 8 a view of a detail of the checking piston device.

In carrying out my invention I provide first a shaft casing 9, to which is secured a spring casing 10 forming also a checking cylinder, the whole being secured to the door as shown

in Fig. 1, so that the shaft 11 will stand in vertical position with the spring casing pointing away from the hinged side of the door. The shaft 11 projects above and below the shaft casing 9, and is rotatably mounted or trunnioned therein as clearly shown in Fig. 5, and provided with suitable stuffing boxes 12 to guard against leakage, and has square or irregular shaped ends 13, designed to form means of attachment for the arm 14, which is designed to swing in a horizontal plane, and has connected at its outer end 15, an extensible connection 16, which is anchored by means of an anchor piece 17, to the casing above the door in the position shown in Fig. 2. The arm 14 will be secured to either one or the other end of the shaft 11, depending upon whether the check is applied to a right or left hand door, the end not engaged by the arm 14 being protected by means of a covering cap 18.

Within the shaft casing 9 the shaft 11 is provided with a bell crank projection 19, and an irregular shaped portion 20, about which it is intended to wrap or wind the flexible, or link connection 21, which has one end at 22 connected to the outer end of the bell crank 19, and the outer end at 23 connected to the checking piston 24, which operates within the checking cylinder 10, and is held against movement to the left by means of a closing spring 25, clearly shown in Figs. 3 and 4, and is provided with the ball valve 26 controlling an opening 27, which when open permits the passage of the checking fluid from one side of the piston to the other, in the opening of the door. The spring casing or checking cylinder 10, is formed of pressed steel and screw threaded into the shaft casing 9, as shown at 28, by which means I am enabled to construct a cylinder and spring casing in a single piece and of very thin pressed steel, requiring but little expense to manufacture, and not being subject to leakage to the same extent as is cast iron or other like cast material because it is of less porous grain. Within the piston 24 is another opening 29, through which passes a tubular rod forming a by-pass 30, the stem of which 31, projects through a stuffing

box 32, so that it can be adjusted from the outside to regulate the speed of closure of the door, the tubular opening 33 of the by-pass affording the passage way for the checking fluid when the door is nearly in closed position. The extent of opening may be regulated by the distance of the end of the tube from the end of the cylinder. In order to eliminate all danger of leakage around the stem 31, the same is arranged so as to control the passage of fluid from the pressure side of the piston to the nonpressure side while the stem is shielded at the same time from the pressure side. In other words the adjustable by-pass is so located that the adjusting stem thereof passes through the casing on the non-pressure side of the piston. The stem of the rod 31 is channeled or flattened as shown at 31^a, as a means of graduating the flow of liquid through the piston, the channel being gradually decreased in capacity toward the place over which the piston stands when the door is near closed position.

The flexible connection 21 is formed of three portions, 21^a, 21^b, and 21^c, all connected together by pivotal connections. The said several parts being so arranged that when the shaft 11 is rotated by the opening of the door, they will wrap around the irregular portion thereof within the shaft casing, in the manner shown in Fig. 4, permitting the piston to be drawn the full length of its stroke within the checking cylinder, part of the cylinder space being occupied by the compressed spring. The entire apparatus takes up but little room. When the door starts to close the shaft rotates in the opposite direction, because of the expansion of the spring 25, and the parts of the connection 21 unwind, and come to a straight line position such as is shown in Fig. 3, at which point, as will be observed, there are provisions made for causing the said flexible connection to take a compression or checking strain, the part 21^a and the part 21^b being each provided with a squared end as shown, whereby it is made impossible for the parts to flex in a direction opposite to the direction shown when the door is open. Before reaching the extreme position at the right shown in Fig. 3, flexure of the connection 21 in a direction upward is prevented by means of the portion 24^a of the piston 24, which also acts as a guide for the stem of the by-pass. By the peculiar arrangement of the shaft and connections shown, it is possible, with this device, to use a shaft capable of rotating through an angle of more than one hundred and eighty degrees and at the same time transmit force continuously in the same direction between the shaft and piston.

Having thus described my invention, what I claim as new, and desire to secure by Letters Patent, is—

1. A door check comprising a checking cylinder, a checking piston therein, a shaft cas-

ing, a shaft mounted therein, a jointed connection between said shaft and the door casing and a connection from said shaft at a point within said shaft casing, to said piston, formed of a plurality of parts constructed so as to wrap about the shaft when the door is opened, and means whereby when the door is closed the said connection between the shaft and the piston acts to carry the compression or checking strain, substantially as described. 75

2. In door closing mechanism the combination of a casing and an actuating arm attached to the door, another actuating arm attached to the frame, a rotatable shaft mounted in the casing and attached to the first named arm, a cylinder extending from said casing and provided with a plunger therein having a spring mounted to directly thrust the plunger in one direction and means for checking its movements, a set of links connecting said rotatable shaft directly with the plunger, whereby the rotation of the shaft reciprocates the plunger in both directions by means of said flexible links. 80

3. In door closing mechanism the combination of a checking cylinder and a piston therein, a by-pass device comprising a graduated hollow stem for varying the escapement passing through the casing of the said cylinder on the non-pressure side of the piston, escapement being in the end of the hollow stem and regulated by the relative proximity of the end to the cylinder end wall. 90

4. The combination with the liquid checking cylinder, and a piston therein, of a by-pass device, comprising an opening through said piston, a rod extending through said opening, a passage controlled by the position of said rod relative to the end of the checking cylinder, and means for determining the position of such rod, substantially as described. 100

5. The combination with a liquid checking cylinder, and a piston therein, of a by-pass device, comprising an opening through said piston, and a hollow rod extending through said opening from the non-pressure side of the piston, said rod having a channel formed therein of smaller capacity toward the end which projects through the piston opening and regulating the escapement by its position with respect to the cylinder wall, substantially as described. 110

6. In a door closing device the combination of a closed casing having a shaft therein provided with a crank arm, a checking cylinder extending from said casing and provided with liquid checking means therein, a plunger attached to said crank arm on the shaft by flexible means capable of taking a thrust, and a coil spring in said cylinder on the opposite side from the liquid checking chamber, substantially as described. 120

7. In a door closing device, in combination with a closed cylinder containing fluid and a piston reciprocating therein, an escapement 125

for the fluid comprising a stationary tubular stem passing through the piston, having an opening through its side and its end outlet placed in position to coöperate with the end 5 wall of the casing to constrict the passage through the stem, to regulate the same, substantially as described.

8. In door closing mechanism the combination with a closed casing having a checking cylinder and being provided with a shaft having a crank arm therein, of a plunger in said cylinder and a series of flexible links designed to wind about the crank shaft on said spindle, said links being provided with shoulders so 10 that in the return motion they may take the thrust upon the plunger to transmit it against the checking liquid as the door is closed, substantially as described.

9. In a door closing and checking device the

combination with a closed cylinder containing 20 a plunger, a link mechanism for directly moving the same, a spring for operating the plunger in the other direction, and a regulator for the escapement of the checking liquid, comprising a rod entirely inclosed in the chamber 25 and extending through the back part of the same on the non-pressure side of the plunger, and provided with a graduated opening there-through to regulate the escapement of the checking fluid, the final escapement through 30 said hollow rod being regulated by the position of the rod with respect to the base of the cylinder, substantially as described.

OSCAR C. RIXSON.

In presence of—

PAUL CARPENTER,
H. W. SMALLEY.
